Primary Examiner — Susan Moon Lee**CLAIM**

The ornamental design for a lifting cat table bowl, as shown and described.

DESCRIPTION

FIG. 1 is a first perspective view of a lifting cat table bowl showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the lifting cat table bowl thereof;

FIG. 10 is an enlarged view of the selected portion in FIG. 1;

FIG. 11 is an enlarged view of the selected portion in FIG. 2;

FIG. 12 is an enlarged view of the selected portion in FIG. 2; and,

FIG. 13 is an enlarged view of the selected portion in FIG. 8.

The broken lines shown in the drawings depict portions of the lifting cat table bowl in which the design is embodied that form no part of the claimed design.
